United States Patent Office.

SAMUEL H. RANSOM, OF ALBANY, NEW YORK.

Design No. 4,046, dated May 17, 1870.

DESIGN FOR STOVE-PLATES.

The Schedule referred to in these Letters Patent and making part of the same.

I, SAMUEL H. RANSOM, of the city and county of Albany and State of New York, have invented and produced a new and original Design for the Plates of a Parlor or Heating-Stove, of which the following is a specification.

The nature of my design is fully represented in the accompanying photographic illustrations, to which reference is made.

I claim as my invention—
The design for the plates of a parlor or heating-stove, as shown.

S. H. RANSOM.
